COMBINED TELEPHONE AMPLIFIER AND REST

William L. Barkin, 1521 Marley Drive,
Los Angeles 46, Calif.

Filed Aug. 22, 1960, Ser. No. 61,850

Term of patent 14 years

(Cl. D26—14)

Figure 1 is a top plan view of a combined telephone amplifier and rest, showing my new design;

Figure 2 is a side elevational view thereof;

Figure 3 is a left-hand end view thereof;

Figure 4 is a right-hand end view thereof;

Figure 5 is a bottom plan view thereof on a reduced scale; and

Figure 6 is a sectional view taken along line 6—6 of Figure 1.

I claim:

The ornamental design for a combined telephone amplifier and rest, substantially as shown.
